FERDINAND MORA CANDA, OF NEW YORK, N. Y.

BALL-ROLLING APPARATUS.

1,399,686.

Specification of Letters Patent.

Patented Dec. 6, 1921.

Application filed November 12, 1919. Serial No. 337,556.

To all whom it may concern:

Be it known that I, FERDINAND MORA CANDA, a citizen of the United States of America, and a resident of the borough of Manhattan, city, county, and State of New York, have invented a certain new and Improved Ball-Rolling Apparatus, of which the following is a specification.

My invention relates to apparatus for forming balls, and is particularly intended for forming, from wrought iron or steel, balls adapted to be used in crusher mills and the like, but is also adapted and intended for forming balls of other materials and for other uses—for example lead shrapnel balls, lead shot, glass balls of various types and sizes, etc. My invention comprises two coöperating disks grooved in the manner hereinafter described, at least one of said disks being arranged to rotate with respect to the other, though preferably both rotate. These disks are so formed relatively that the space between them contracts gradually, through the grooved space. Into the wider part of the space between the disks the end portion of a rod to be formed into balls may be introduced; whereupon, the disks, or at least one of them, being in rotation, the ridges between their grooves divide the bar into sections which, by the action of the grooves, are rolled into ball form. Other features of my invention will be pointed out hereafter.

The object of my invention is to form balls, particularly of iron or steel, relatively inexpensively, rapidly, and by simple apparatus.

I will now proceed to describe my invention with reference to the accompanying drawings, and will then point out the novel features in claims.

In said drawings:

Figures 1 to 5 inclusive are more or less diagrammatic, but illustrate the essential features of apparatus embodying my invention, Fig. 1 being a top view of such apparatus, Fig. 2 a vertical section on the line 2—2 of Fig. 1, Fig. 3 a front elevation of the apparatus, Fig. 4 a top view of the bottom die, and Fig. 5 a bottom view of the top die.

Fig. 6 shows a top view and Fig. 7 a side elevation and partial section of more complete apparatus embodying my invention.

Referring first to Figs. 1 and 2: 1 designates a top die-disk, and 2 a bottom die-disk,

mounted respectively on shafts 3 and 4, by which they may be rotated. As appears particularly from Fig. 5, the top disk, 1, is provided on its end face with a series of concentric grooves 5 of substantially semi-circular profile. The top face of the lower disk, 2, is divided into alternate segments 6 and 7, of which 6 are grooved, and 7 are not grooved; and moreover the said grooved segments 6 have inclined surfaces, so that the spaces between these grooved segments 6 and the bottom surface of the disk 1 grow progressively narrower. Moreover, preferably the initial portion 6^a of each such grooved segment 6 is inclined or pitched more sharply at the rear (*i. e.*, near the center of the disk) than at the front; the result being that in the active ball forming portion 6^b of each such segment the grooves are of nearly equal length, notwithstanding differences of radial distance.

The operation of my improved ball rolling machine is as follows: The disks 1 and 2 being in rotation in opposite directions, a bar of material to be rolled into balls is introduced radially at a time when one of the ungrooved segments 7 of the lower disk is in front of the point of introduction, this bar being pushed back close to the central hub 9 of disk 1, which forms an end stop for the bar. Rotation of disk 2 brings the initial sharply-tapered portion 6^a of one of the grooved segments 6 against the bar and thereby the bar is rolled between disks 1 and 2, the ribs of the two disks cutting into the material of the bar and dividing it into ball-sections, which, particularly after these sections have reached the more gradually-tapering portion 6^b, are rolled into the form of balls and are severed, falling into the next ungrooved segment 7, wherefrom they are expelled by centrifugal force or otherwise, as for example, by hand. To facilitate expelling the balls, the floors of the segments 7 may slope downward and outward as shown, so that the balls tend to roll out.

Ordinarily, the bar to be rolled into balls is of a length considerably greater than the distance from the hub 9 to the periphery of disks 1 and 2. Consequently, as soon as one section of this rod has been rolled into balls, and, in the process of rolling, has been cut off from the main bar, said bar is pushed in for a further distance as soon as its end is opposite another ungrooved segment 7 of the lower disk, and the operation repeated.

until too little of the bar remains for insertion in the manner described. Of course, when the bar is of a material requiring heating to soften it to condition it for rolling, 5 that bar is presented to the mill in a properly heated condition.

Figs. 6 and 7 show a ball mill operating on the above principle, but wherein the structural details have been elaborated some- 10 what from the diagrammatic forms shown in Figs. 1 to 5 inclusive. In this arrangement, the two disks, here designated as 1^a and 2^a, have beveled gear-rings 10 on their peripheries, and are driven by a bevel pin- 15 ion 11. Furthermore, the lower disk, 2^a, is supported on substantially peripheral bearing rollers 12 carried by a massive bed plate 13. The upper disk, 1^a, is mounted on a central shaft 14 itself having suitable bear- 20 ings, but upward thrust on the disk 1^a due to resistance afforded by the material being rolled is taken by substantially peripheral rollers 15 working against a backing ring 16 mounted in top disk 17 and held against 25 the rollers by stiff springs 17^a. Base disk 13 and annular top disk 17 are held together by massive bolts 18.

What I claim is:—

1. In a ball rolling apparatus, the combi- 30 nation of two coöperating ball rolling disks, rotatable one with respect to the other, one of said disks having alternate grooved and ungrooved segments, the former elevated above the latter, the surfaces of the un- 35 grooved segments being inclined downwardly and outwardly to facilitate discharge of the finished balls.

2. In a ball rolling apparatus, the combi- 40 nation of two coöperating ball rolling disks, rotatable one with respect to the other, one of said disks having alternate grooved and ungrooved segments, each grooved segment comprising a relatively steeply inclined portion merging into a less steeply 45 inclined portion.

3. In a ball rolling apparatus, the combi- 50 nation of two coöperating ball rolling disks, rotatable one with respect to the other, one of said disks having alternate grooved and ungrooved segments, each grooved segment comprising different portions of different degrees of inclination.

4. In a ball rolling apparatus, the combi- 55 nation of two coöperating ball rolling disks, rotatable one with respect to the other, one

of said disks having alternate grooved and ungrooved segments, each grooved segment comprising an introductory steeply inclined portion and a further less steeply inclined portion, the inner part of the less steeply 60 inclined portion being of greater angular length than the outer part, whereby inner grooves may be of nearly the same linear length as outer grooves.

5. In a ball rolling apparatus, the combi- 65 nation of two coöperating ball rolling disks, rotatable one with respect to the other, at least one of which disks is grooved, at least one of which disks is provided with means for the reception of material to be rolled, 70 and at least one of which disks is provided with a central hub forming an end stop for the material to be introduced.

6. In a ball rolling apparatus, the combi- 75 nation of two coöperating ball rolling disks, means for rotating one with respect to the other, and a spring backing for one of said disks operating upon said disk adjacent the periphery thereof.

7. In a ball rolling apparatus, the combi- 80 nation of two coöperating ball rolling disks, means for rotating one with respect to the other, a backing plate for one of said disks, springs working against said backing plate, and means for receiving the thrust of said 85 springs.

8. In a ball rolling apparatus, the combi- 90 nation of two coöperating ball rolling disks, means for rotating one of said disks with respect to the other, a backing plate for such rotatable disk, bearing rollers between said rotatable disk and backing plate, springs bearing against said backing plate, and means for receiving the thrust of said 95 springs.

9. In a ball rolling apparatus, the combi- 100 nation of two coöperating ball rolling disks, a frame in which said disks have central bearings permitting their rotation, means for rotating said disks, and peripheral bearings for said disks, one of such peripheral bearings having a yieldable spring-pressed backing.

In testimony whereof I have signed this specification in the presence of two sub- 105 scribing witnesses.

FERDINAND MORA CANDA.
